UNITED STATES PATENT OFFICE

JOHN T. BLUFF, OF COMPTON, CALIFORNIA

DISPLAY DEVICE

Application filed January 7, 1930. Serial No. 419,122.

The present invention relates to improvements in display devices, and has for an object to provide an improved display device more particularly for use on automobiles or 5 other vehicles, in which advertising matter, flags, symbols and other devices may be supported on the vehicle in a prominent position and in an attractive manner.

Another object of the invention resides in 10 providing an improved display device in which numerous flags, letters and symbols may be grouped into ornamental organizations for the purpose of greeting various organizations, clubs, etc., which happen to be 15 holding conventions in the locality.

A further object of the invention resides in providing an improved display device in which the bumper of the vehicle may be utilized for the purpose of carrying symbols 20 and other insignia, and which will involve but a slight modification of the bumper structure and can be installed therein inexpensively.

With the foregoing and other objects in 25 view, the invention will be more particularly described hereinafter, and more particularly pointed out in the appended claims.

In the drawings, in which like symbols refer to like or corresponding parts throughout the several views,

Figure 1 is a fragmentary perspective view of a motor vehicle shown equipped with my improved display device.

Figure 2 is a top plan view with parts 35 broken away, showing the device detached from the vehicle and without the display symbols or members therein.

Figure 3 is a front elevation partly broken away, showing several of the symbols in 40 place therein.

Figure 4 is a cross sectional view taken on the line 4-4 in Figure 2.

Figure 5 is a front elevation of a vehicle 45 shown equipped with a modified form of bumper constructed in accordance with the present invention.

Figure 6 is a top plan view of the bumper 50 detached from the vehicle and partly broken away.

Figure 7 is a longitudinal section taken along the line 7-7 in Figure 6.

Figure 8 is a transverse section taken on the line 8-8 in Figure 6.

Figure 9 is a perspective view of one of 55 the letters employed, and

Figure 10 is a similar view showing a slight modification.

Referring more particularly to the drawings, and for the present to Figures 1 to 4, 60 inclusive, 12 represents generally a motor vehicle and 13 the top or roof thereof having the sun visor 14 extending above and forwardly of the wind shield 15.

The top and its supports are taken advantage of in this instance to support the improved display device, which is held thereto as by the use of bracket arms 16, which are clamped, screwed or otherwise secured to the top of the car in a manner to avoid injury 65 thereto.

These supporting arms 16 carry at their outer ends a cylinder or tube 17 having therein a strong steel coil spring 18, or other resilient material, the convolutions of which are closely wound, whereby to form adjacent clamping members for tightly gripping 75 therein the staffs 19 of flags 20, the prongs 21 of letters 22, and the feet 23 of an elk or other symbol 24.

These various flags, letters and symbols are received into the tube 17 through a slot 25 in the upper side thereof, and the prongs, flag staffs, etc., preferably pass entirely 80 through the convolutions of the spring 18 and downwardly through a slot 26 at the lower portion of the tube 17. For convenience in manufacture, the tube may be constituted of two semi-cylindrical sections spaced from 85 one another to provide the upper and lower slots referred to. The two sections of the tube may be held spaced apart to provide the slots by the action of the coil spring 18, which will be selected as of a proper diameter 90 with reference to the tube to secure this result. The two tube sections may be drawn together compressing the spring 18 to a desired amount consistent with the width of the slots desired, and this is effected preferably by the use of the clamp carried by the 95 100

supporting arms 16. The arms 16 carry the half clamp sections 27 which embrace the rearmost section of the tube 17. These rear clamp sections 17 have perforated lugs 28 adapted to mate with similar perforated lugs 29 on the forward complementary clamp sections 30 which embrace the forward members of the tube. By tightening the bolts 31, which pass through the perforated lugs, or loosening such bolts, the width of the slots 25 and 26 and the degree of compression of the steel coil spring 18 may be regulated.

The tube may or may not be provided with a lining of rubber or fiber between the tube and the spring 18, whereby to stop any rattling of the spring in the tube incident to the vibration of the vehicle.

Referring to Figures 5 to 10, inclusive, the adaptability of the invention for use as a bumper bar is shown, it being understood that the device is enlarged and strengthened to suit it to this purpose. Such a bumper bar is shown at 32, being preferably cylindrical in general contour and being hollow to receive the strong steel coil spring 33 which may be spaced from the interior 4 of the cylindrical bumper bar 32 by means of a rubber, fiber or other lining 34. This lining may be formed in strips, as shown in Figure 8.

The bumper bar 32 is provided with removable end caps or horns 35. Within these horns, the ends of the tube carry disks 36 removably held in place by set screws 37, or other appropriate means. The disks are provided with threaded openings to receive therethrough the screw shafts 38. The inner ends of the screw shafts 38 carry disks 39 which slide back and forth, either compressing or releasing the coil spring 33.

The bumper bar 32 is provided with a series of upper perforations 40 and with a series of lower perforations 41 disposed in registry with the upper perforations, whereby to receive the flag staffs and the prongs of the letters or symbols, as shown in Figures 5 and 7.

The bumper bar is held upon the vehicle by the brackets 42 in the ordinary way.

Referring to Figure 9, one of the letters 22 is shown having two prongs 21 spaced apart and provided with lower pointed ends to facilitate the prying apart of the helices of the spring and for the entrance of the prongs between such convolutions.

In Figure 10, a single prong 21^a is shown of a similar construction, and it will be understood that one or more prongs may be carried by the letters or by the symbols used.

It will also be understood that a small lamp for the purpose of flood lighting equipped with similar prongs may be held in the device and illuminate the display.

In the use of the device, in Figure 1, I have shown two flags 20 set in the device at opposite sides of the elks insignia and

initial letters. A flood light might also be arranged to play upon this display at night. It will be understood that the prongs of the letters and symbols and the staffs of the flag extend through the upper and lower slots and through the convolutions of the spring, and that great stability is given to the display devices by the engagement of such spring and staffs with the side walls of both upper and lower slots, and in this way, the display is adapted to withstand that considerable pressure encountered in automobile driving.

A similar situation exists in the modified form of the device shown in Figures 5 to 10, the prongs of the letters and the staffs of the flag extending through both upper and lower series of perforations 40 and 41, and the devices also being held against lateral movement by the side walls of such perforations, so that the display is constantly maintained in its original attractive position and resists all jarring out of place.

It will be obvious that many changes in the construction, combination and arrangement of parts could be made, which could be used without departing from the spirit of my invention, and I do not mean to limit the invention to such details, except as particularly pointed out in the claims.

Having thus described my invention, what I claim and desire to secure by Letters Patent of the United States is:—

1. An improved display device comprising a coil spring, two semi-cylindrical tube sections assembled on said coil spring and means for compressing the sections selectively upon said spring.

2. An improved display device comprising a horizontally disposed tube having openings in its upper and lower portions, means for holding the same substantially transversely of a vehicle, a coil spring mounted in said tube, lining material between said coil spring and the tube, and means for adjusting the tension of the coil spring.

3. An improved display device comprising a tube having openings in its upper and lower portion, a coil spring mounted in said tube, means in the ends of the tube for selectively compressing the coil spring, and end caps on the tube for concealing the adjusting means.

JOHN T. BLUFF.
